UNITED STATES PATENT OFFICE.

THEODORE B. STEVENS, OF CLEVELAND, OHIO.

SPRING-LATCH.

No. 874,633.

Specification of Letters Patent.

Patented Dec. 24, 1907.

Application filed September 24, 1906. Serial No. 335,914.

To all whom it may concern:

Be it known that I, THEODORE B. STEVENS, a citizen of the United States, residing at Cleveland, in the county of Cuyahoga and State of Ohio, have invented a certain new and useful Improvement in Spring-Latches, of which the following is a full, clear, and exact description.

The drawing shows the invention in the best form now known to me.

Among the desirable characteristics of the lock shown, due to the invention, are the following. It is cheap in construction, and very neat in appearance; it is spring-actuated, and latches automatically when the door is closed, but may be subsequently moved to draw the door more closely against the door jamb; it is reversible, that is to say it may be assembled so as to be used either upon the right or left side of the door; It and its strike are so constructed that they may be secured to the door and door frame respectively in the precise relative position they should occupy to properly engage with each other; and the means for so determining the position of said parts also act to relieve the hinges of the door from strain when the latch is being operated to draw the door tightly closed. Moreover, the latch is provided with a simple form of lock contrivance which serves the double purpose of a lock, and of a bolt for holding the parts of the latch in operative position.

In the drawing, Figure 1 is a front elevation of the latch and its strike applied to a door and door frame. Fig. 2 is a front elevation of the device when the latch member has been removed and a portion of the strike has been cut away. Fig. 3 is a sectional view in the plane indicated by line 3—3 of Fig. 1 looking to the left. Fig. 4 is a horizontal sectional view in the plane indicated by line 4—4 of Fig. 2. Fig. 5 is a bottom view of the latch member of the device. Fig. 6 is a vertical sectional section in the plane indicated by line 6—6 of Fig. 2. Fig. 7 is an elevation of the key; and Fig. 8 is an elevation of the locking stud showing the same in a position at right angles to that in which it appears in fig. 4.

Referring to the parts by letters A represents the base of the latch. It has a raised circular middle part and an outwardly extended annular flange, adapted to lie against the door to which the base plate may be at-

tached by means of screws J passing through the raised middle part.

B represents the latch member which includes a rearwardly extended cylindrical flange b, the latch b' and an operating handle b². This latch member is provided with a rearwardly extended cylindrical stud b⁴ by means of which it is pivoted to the base plate A; and also with a rearwardly extended post b⁶. It is necessary that all of the parts of the latch member mentioned shall be rigidly connected, but it is not necessary that they should all be made of one piece. In fact, in practice it is preferred that the flange b shall be part of a cap made of stamped metal; and that the rest of this member shall be malleable casting in the form of a bar b⁵, having the clutch on one end, the handle b² on the other. The stud b⁴ and a post b⁶ are formed on the under side of said bar. Both project through holes in the top of the cap; and a part of this post b⁶ just inside of the cap is upset against said cap. A finger b⁷ on the rear side of the latch is bent into a notch in the lower edge of the flange of the cap; and this, together with the upsetting of the body of post b⁶, suitably connects the two parts of the latch member. The stud b⁴ passes down through the centrally placed circular hole a³ in the base plate; which hole has two radial branches a⁴. When the base plate is made of stamped metal, these branches are formed by pressing the metal upward so as to additionally form the posts a⁵.

C represents a coiled spring having hooked shaped ends. One of the hooked shaped ends engages in a hole in the post a⁹. This post is preferably formed by punching up a part of the base plate, thereby forming also a hole whose two edges a² a² serve as shoulders 95 having a function to be explained presently. The coil of the spring surrounds the stud b⁴ and also embraces the posts a⁵ a⁵.

D represents the strike which is of the usual form, and projects forward from a plate d which is to be secured to the door frame by means of screws. On each side of this plate, adjacent to the strike are two recesses d' d². On the base plate A is a tongue a⁷, of such size that it fits loosely into one of these recesses.

In applying the latch and strike to a door and its frame, the base plate and strike plate are respectively secured in place as shown in Fig. 2, at which time, it will be seen, the 110

tongue a' lies in one of the said recesses, as d' . The spring C is then put in the position substantially as shown in Fig. 2. The latch member is then attached to the base plate by 5 first passing the stub b^4 and the radiating arms b^8 thereon through the hole a^3 and its branches a^4 . The latch member is then turned about one quarter of a revolution which carries the arms b^8 under the base 10 plate and thereby prevents the removal of said latch member. When the parts are so connected the flange b embraces the raised part a of the base plate and engages with the marginal flange a' . As the latch member is 15 turned, the post b^6 will come into engagement with the hooked end of the spring C, and will wind up the spring, which thereafter tends to turn said latch member backward. It is now required that some means be provided for holding the latch member in an 20 operative position. Any device which will permit the latch member to turn a short distance only will serve; that is to say enough to properly engage and disengage the strike; 25 but the preferred means consists of a locking bolt E having a cylindrical body which passes through and is rotatably mounted in a circular hole in the top of the latch member. A spring G is provided for drawing this bolt 30 inward, said spring being, in the form shown, a coiled spring thrusting against the inner face of the cap, and having its lower end projected into a hole in the bolt. On the lower end of this bolt, and extending diametrically 35 across it is a narrow downwardly extended rib e, which projects into the space between the shoulders a^2 on the plate A. When this bolt is in the position shown in Fig. 4 the latch is only permitted to turn upon its axis 40 the short distance which said rib may move between said shoulders, but this is sufficient to enable it to perform its functions. This locking bolt is provided with a head e' having on the under side the beveled lugs e^2 . These 45 are adapted to enter grooves b^9 in the top of the latching member, there being two of these grooves set at right angles to each other. One of them shows in Fig. 1 and the other shows in Fig. 4. When it is desired to 50 lock the latch, this locking bolt is turned one-quarter of a revolution, whereby the ends of the rib e are brought into practical engagement with the two shoulders a^2 , as shown by dotted lines in Fig. 2; and this prevents any 55 effective movement of the latching member upon its axis. (See Fig. 2). Two holes c^3 may be made in the top of the locking bolt for the reception of two prongs k on the lower end of a key K, by means of which the bolt 60 may be turned.

When the latch member B is being passed into the described engagement with the base plate, the lower end of this bolt E will engage with the top of the base plate, and will therefore be pushed forward slightly. When the

latch member is turned upon the base plate to its operative position the bolt will be forced by its spring down between the shoulders a^2 a^2 . Therefore, all that one has to do in order to connect the parts in operative position is to pass the stud b^4 through the hole in the locking plate and then turn said latch member around to its operative position. The arms b^8 prevent the latch-member from being drawn out of engagement with the 75 base plate; and the engagement of the bolt E between the shoulders a^2 prevents the latch member from being turned back out of the operative position.

The described latch is reversible. It is 80 therefore applicable to either the right or left side of the door. It is shown applied to the left side; but in order to adapt it for application to the right side all that is necessary to do is to turn the spring C over so that 85 the hook on its free end faces in the opposite direction to that shown. When the latch member is then applied to the base plate it is turned around to the operative position in a direction contrary to that in which it is 90 turned for assembling the device in the manner first described. The same post b^6 will be brought into engagement with the hook on the free end of the spring, and thereby the spring will be wound up; and the bolt E will 95 snap in between the two shoulders a^2 and retain the parts in the operative position.

When the spring C is turned over, its free end will, obviously, lie directly upon the base plate. It might, therefore, slip under the 100 post b^6 , and thereby render the device inoperative, unless the end of said post were very close to the base plate. Such action is not liable to happen; but all chances for its so happening are practically eliminated without additional expense by pressing an arc-shaped groove a^6 in the base plate, and making post b^6 long enough to project into said groove below the plane of the top of said base plate. The recess d^2 on the left side of the 110 strike plate is for use in positioning the parts of the latch when it is assembled on the right side of the door.

The front surface of the latch is beveled for engagement with the strike shoulder; 115 wherefore after said latch has engaged with said shoulder one may, by applying sufficient force to the handle of the latch member, force this beveled front surface down, with the result of drawing the door closed very 120 tightly. When the latch is so manipulated, it is obvious that an upward strain is imposed upon the door. All injurious effects of this upward strain are eliminated by the engagement of the tongue a' in one of the notches, 125 d' d^2 in the strike plate.

While the drawings show what is believed to be the best embodiment of the invention, and while said embodiment has been described in detail, it is obvious that many 130

minor changes in construction may be made, and it is not intended that the claims shall be limited to this specific construction, except as such limitations clearly appear in the appended claims.

Having described my invention, I claim:

1. In a latch, the combination of a base plate and a latch member pivoted to said base plate and capable of being disconnected therefrom only when in certain positions, and a spring acting to turn said latch member in the latching direction, — said base plate and latching member having, the one two shoulders and the other a movable device capable of being moved between said shoulders after the latching member has been pivoted to the base plate and has been turned into operative position, whereby the latch member is held in operative position and prevented from being turned relative to the base plate to a position where it can be disconnected therefrom.
2. In a latch, the combination of a base plate and a latch member pivoted to said base plate and capable of being disconnected therefrom only when in certain positions, and a spring acting to turn said latch member in the latching direction, — said base plate and latching member having, the one two shoulders and the other a movable device capable of being moved between said shoulders after the latching member has been pivoted to the base plate and has been turned into operative position, whereby the latch member is held in operative position and is prevented from being turned relative to the base plate to a position where it can be disconnected therefrom, and a spring for moving said movable device into the described position between said shoulders.
3. In a latch, the combination of a base plate provided with two shoulders and a forwardly projecting post a^9 , a latch pivoted to said base plate and having a rearwardly projecting post b^6 , a coil spring surrounding the axis of the latch and engaging at its ends respectively with the posts b^6 and a^9 , and a movable device carried by the latch and adapted to be moved between said shoulders whereby through the engagement with said shoulders the movement of said latch member upon its axis is limited and the latch held in operative position.
4. In a latch, the combination of a base plate having two shoulders a^2 , a latch member pivoted thereto, a spring operated to turn it in the latching direction, a spring bolt carried by said latching member and capable of being moved endwise and being turned upon its axis and having a narrow downwardly projecting rib on its under side which projects between the said shoulders.
5. In a latch, the combination of a base plate having two shoulders a^2 , a latch member pivoted thereto, a spring operated to
- turn it in the latching direction, a spring bolt which passes through a hole in said latching member and is capable of being moved endwise and being turned in the same, and having a narrow downwardly projecting rib on its under side which projects between the said shoulders, — said latch member having radiating grooves adjacent to said hole and said bolt having a beveled lug adapted to enter either of said grooves.
6. In a latch, the combination of a raised cylindrical base plate having a marginal flange, and having a centrally placed circular hole with laterally extended branches, a latching member having a rearwardly projecting cylindrical flange and a stud provided with a laterally extended arm, a coil spring within said flange tending to turn said latching member relative to the base plate, said base plate and latching member being respectively provided with two shoulders and with a piece projecting between them and adapted to engage with them and thereby to limit the movement of the latching member upon its axis.
7. In a latch, the combination of a raised cylindrical base plate having a marginal flange and centrally placed hole having laterally extending branches and having another hole near its edge and having also a forwardly extending post, a latch member carrying a rearwardly extended pivot stud provided with laterally extended arms and having also a rearwardly extended post b^6 , a spring surrounding the pivot post engaging with the two posts secured respectively to the base plate and latch member, and a spring actuated locking bolt carried by the latch member and projecting into the hole near the margin of the base plate.
8. In a latch, the combination of a raised circular base plate having a marginal flange, said base plate being provided with centrally placed circular hole and two shoulders, with a latch member having a rearwardly extended cylindrical flange which embraces the raised circular part of the base plate and bears against said flange, — said latch member has also a rearwardly extended cylindrical stud which passes through the hole in the base plate, means preventing the withdrawal of said stud from said hole, a coiled spring surrounding said stud and engaging at its ends respectively with parts of the base plate and latch member, a spring bolt carried by the latch member and adapted to engage between the two shoulders on the base plate.
9. In a latch, the combination of a raised circular base plate having an outwardly extended marginal flange, said base plate being provided with two shoulders a^2 , and with a centrally placed circular hole having laterally extended branches and with a forwardly projecting post, with a latch member having

- a rearwardly extended cylindrical flange which embraces the raised part of the base plate, and engages with the marginal flange thereof, said latch member having also a centrally placed and rearwardly extended cylindrical stud provided with laterally extended arms, and having also rearwardly projecting post, a coiled spring surrounding the pivoting stud and having hook shaped ends which engage with the two posts carried by the base plate and latch member respectively, and a spring bolt carried by the latch member and adapted to engage between said shoulders a^2 .
15. In a latch, the combination of a raised circular base plate having an outwardly extended marginal flange, said base plate being provided with two shoulders a^2 , and with a centrally placed circular hole having laterally extended branches and with a forwardly projecting post, with a latch member having a rearwardly extended cylindrical flange which embraces the raised part of the base plate, and engages with the marginal flange thereof, said latch member having also a centrally placed and rearwardly extended cylindrical stud provided with laterally extended arms, and having also rearwardly projecting post, a coiled spring surrounding the pivoting stud and engaging at its end with the two posts carried by the base plate and latch member respectively, a spring bolt carried by the latch member, said bolt having a narrow diametrically disposed rib upon its rear end which is adapted to lie between the two shoulders a^2 , said bolt being adapted to be turned upon its axis so that said rib may stand crosswise or lengthwise between said shoulders, and thereby prevent or permit a limited movement of the latch member.
11. In a latch, the combination of a base plate having an arcal depression in its surface and having a forwardly projecting post, a latch member pivoted to said base plate and having a post extending therefrom into the said arcal groove, a coil spring surrounding the pivot of said latch member and engaging with said two posts, and means limiting the movement of the latch member upon its axis.
12. In a latch, a latch member comprising
- a cap having a rearwardly extended cylindrical flange, and a latch bar having a pivot stud which passes centrally through the top of said cap and having also a post which extends through a hole in said cap and has an upset portion engaging with the under surface of said cap and which also has a finger b^7 which is bent into a notch in the marginal flange of said cap.
13. In a latch, the combination of a base plate having a tongue b^7 , a strike plate having notches d^2 , d^3 ,—either of which is adapted to receive said tongue,—and having a strike which projects forward from between said notches, with a latch member pivoted to said base plate and adapted to engage with said strike.
14. In a latch, the combination of a base plate having a tongue b^7 , a strike plate having notches d^2 , d^3 ,—either of which is adapted to receive said tongue,—and having a strike, with a latch member pivoted to said base plate and adapted to engage with said strike, the front face of the latch member being beveled for engagement with the shoulder on the strike.
15. In a latch, the combination of a base plate having a tongue b^7 , and a strike plate having a recess d^2 and a strike with a rearwardly faced shoulder, with a latch member pivoted to said base plate, a spring moving it in the latching direction, means limiting the movement of said latch upon its axis, said latch having a bevel front face for engagement with the shoulder on the strike.
16. In a latch, the combination of a raised cylindrical base plate having an outwardly extended marginal flange and an integral tongue lying substantially in the plane of said flange, with a latching member having a rearwardly projecting cylindrical flange and a stud by which said member is pivoted to the base plate, and a strike plate having a forwardly projecting strike and having near one edge a shallow notch adapted to receive said tongue.

In testimony whereof, I hereunto affix my signature in the presence of two witnesses.
